UNITED STATES PATENT OFFICE.

WILLIAM H. CANNARD AND GLENN A. SHAFFER, OF GREEN BAY, WISCONSIN, ASSIGNEES TO SAID CANNARD.

SHEET-INTERFOLDING MACHINE.

Application filed September 29, 1921. Serial No. 504,023.

To all whom it may concern:

Be known that we, WILLIAM H. CANNARD and GLENN A. SHAFFER, a citizen of the United States, and a subject of the King of Great Britain, respectively, residing at Green Bay, in the county of Brown and State of Wisconsin, have invented certain new and useful Improvements in Sheet-Interfolding Machines, of which the following 10 is a specification, reference being had therein to the accompanying drawing.

This invention comprises a sheet interfolding machine.

It is contemplated to provide a machine of 15 the character specified, which will take material in sheets from a source of supply, cut, fold, interfold a portion of one sheet within a portion of another, count the number of sheets so interfolded, deliver them in compact form, and offset a portion of the delivered product when a predetermined number of sheets have been passed out.

Another object of the invention is to utilize the action of rotating members in the accomplishment of these ends, whereby reciprocating parts are eliminated, thus speeding up the production considerably and eliminating wear and vibration.

Other objects and advantages will in part 30 be apparent, and in part be brought out more fully in the description which follows.

Drawings illustrating a preferred embodiment of the invention are hereto annexed, and in which:

35 Fig. 1 is a view in side elevation, certain portions being in section and showing one embodiment of the various components in a complete machine;

40 Fig. 2 is a diagrammatic view in vertical section showing the various steps of cutting, folding, interfolding and delivery, and the positions of certain components during this cycle of operations;

45 Fig. 3 is a view in longitudinal section through one of the rotary cylinders, on the line 3—3 of Fig. 4;

50 Figs. 4 and 5 are views in vertical section through one of these cylinders on lines 4—4 and 5—5, respectively, of Fig. 3;

55 Fig. 6 is a view in side elevation of one of the rotating cylinders and illustrating its connection with a source of rotary movement;

Fig. 7 is a detail view in cross section 55 through one of the pinch-rolls, and showing

a manner of mounting the movable pinch-bar.

In these views, 1 designates a frame work comprising uprights and cross-pieces constituting a support for the working parts of the machine. Journaled in suitable bearings in its upper portion are shafts 2, carrying guide-rolls 3, adapted to lead webs of material from a source of supply, such as stock-rolls 4 shown in Fig. 2.

65 Between these rolls there is mounted a guide or separator 5, having a knife-edge close to the bight of the rolls and adapted to guide webs of material fed from opposite sides of the guide-rolls, singly and in separated arrangement, to opposite sides of a cutter-bar 6. This is suitably mounted in the framework below the guide or separator 5.

70 The lower edges of the cutter-bar are serrated, as at 7, and coact with similarly-formed blades 8, disposed on rolls 9. These rolls are carried on shafts 10 journaled suitably on the framework, and are placed directly in the line of travel of the web as it 75 passes through the guide-rolls.

75 The knives are disposed upon the rolls in such a way that they will come into alternate engagement with the cutter-bar, and the two sets of rolls are connected together by suitable gearing (not shown) and which in turn is in driving connection with a source of rotary movement which will be later described.

80 From the cutter-rolls, the material passes to a folding and interfolding instrumentality 85 which will now be described: This includes coacting cylinders or drums 11, mounted for rotation on shafts 12 suitably journaled in the framework. These drums are driven in opposite directions through gearing 13, in 90 mesh with a pinion 14 on a shaft 15 which constitutes the main-drive shaft of the machine.

95 Each drum or cylinder has end-portions 16 connected by brace-members 17 and bolts 100 or the like 17', spaced apart around the circumference of the end-portions, and between which there is mounted (so as to be effective on the periphery of the drums) a series of pinch or folding rolls 18, and a series of 105 tucker-rolls 19. These are in alternate arrangement, first a set of pinch-rolls and then a tucker-roll, etc., in any suitable number and disposed about the circumference of the drum. The mounting and arrangement is 110

such that a tucker-roll on one drum will contact with a set of pinch or folding rolls on the other drum at a predetermined time, the accuracy of which is assured by a suitable instrumentality, such as gearing here shown.

The arrangement of the gearing will be best seen with reference to Fig. 4: Each drum-shaft is stationary, that is, it is mounted securely against rotation in the 16 casing of the machine. At one end of the drum-shaft there is secured (as a part of the shaft) a pinion 20. This is in mesh with a series of idler-gears 21, suitably mounted for rotation on the end-portion of 18 each drum. In mesh with the teeth of these idler-gears are pinions 22, carried by each tucker-roll, and the arrangement is such that a protruding tucker-member 23, extending outwardly along the length of the 20 roll, will always maintain a horizontal position and point and extend between the bight of the pinch or folder rolls when these two instrumentalities come into co-active engagement at the center-line of the 22 drums, as shown in Fig. 2. This horizontal arrangement is effected by timing, making the pinion on the drum-shaft 12 of the same ratio as the pinion 22 on the tucker-roll; and, in this way, the tucker-roll will maintain a fixed, definite and unchanging position with relation to the drum-axle, no matter what the rotation of the drum itself 25 may be. These drums are mounted for rotative movement on their respective shafts 26 in suitable anti-friction bearings 22', the drums being driven as stated above.

Each set of pinch-rolls comprises two rolls, mounted loosely in the ends of the drums. One of these rolls carries along its 40 outer edge a projecting portion 24, extending along the outer face of the roll and adapted to coact with a pinch-bar 25, mounted similarly on the other roll of each series. Bar 24 is usually fixed with relation to the roll, while bar 25 is spring-pressed to allow for various sizes of material and to aid in effecting release. To permit movement of bar 25, it is mounted in 45 a groove or slot extending longitudinally 50 of the pinch-roll and in which it has a slideable bearing. It is retained therein as by screws 25^a passing through the bar and threaded into the body of the roll. A space 55 25^b is provided in the roll extending around the screws 25^a and constitutes a housing for a spring 25^c. This spring bears at one point against a portion of the roll and at another against the movable pinch-bar, holding it at the limit of its outward movement with a yielding pressure. A jam-nut 60 25^d limits the position of the screw 25^a in the roll and acts to lock the screw 25^a in adjusted position.

Referring to Figs. 4 and 5, the action of 65 these pinch-rolls will be described: These

rolls are given an initial position in the drum equivalent to that shown in Fig. 2, where the set of pinch-rolls is shown in co-action with a tucker-bar at the horizontal center-line of the drums. The end of each roll carries, and has fixed thereto, a pinion 70 25', which is fixed in ratio to the pinion 20, carried by the drum shaft 12. The pinion on the roll which carries the fixed pinch-bar is in mesh with an idler 21, while the 75 pinion on the roll having the movable bar is in mesh with the pinion carried by its coacting pinch-roll. The effect of this arrangement is to maintain the roll having the fixed-bar 24 in unchanging relation to the drum shaft 12 and insure the bar 24 being always in its initial position when it comes to the horizontal center-line of the 80 drum. The roll carrying the movable pinch-bar will make one revolution to each 85 revolution of the drum, but is timed to be always in its proper position to coact with the other roll and tucker-bar when they come together at the central or folding position, as shown in Fig. 2. In other words, 90 the timing is such that both pinch-bars coact to take the portion of the web presented to them by the tucker-bar when these instrumentalities come together at the horizontal center-line of the drums. As soon as 95 this has been effected, the pinch-roll having the movable pinch-bar will rotate on its axis to effect a release of the gripped web at a point about sixty degrees (60°) below the initial point of gripping. 100

Means are provided for assisting in the release of the web from the pinch-rolls; and, to this end, there are mounted on shafts 26, set in the framework on a line about where the web is released from the 105 pinch-rolls on each drum, brushes 27. These receive a rotative movement through a belt driven from a pinion 28, secured to the drive-shaft 15, the belt being carried around an idler 29, and over one and under another 110 pinion 30 mounted on the shafts 26 carrying the brushes. Clockwise rotation of drive-shaft 15 will cause the brushes to rotate inwardly toward each other to brush the edge of the folded web as it leaves the 115 pinch-rolls.

Means are provided for counting the number of interfolded sheets passing through the folding-drums; and, to this end, there is mounted on the end of the drive-shaft 15, a 120 pinion 31. It is in mesh with a train of gears 32 constituting a counting-mechanism. One of these carries a sprocket-gear 33 over which passes a chain 34. This is carried around an idler 35, thence over one and under another sprocket 36. These latter are mounted on the ends of shafts 37 extending across the machine in the path of travel of the interfolded sheets as they leave the 125 brushes. There are cams 38 mounted on 130

these shafts, and the arrangement is such that, after a predetermined number of sheets have passed through the drums, the cams are rotated to push a portion of the folded 5 sheets out of alignment with the rest. As this mechanism is to be the subject-matter of a separate application, it is only referred to generally here.

From the counter-cams, the sheets pass 10 along ways 39 or the like, to a conveyor 40 driven from one of the sprockets 36.

As the webs are cut alternately, the cutting is timed so that the cut edge of one web will be placed about centrally between 15 the two edges of the sheet cut from the opposite web, and the arrangement of the folding-drums and the instrumentalities they carry is such that the pusher-bar will push the free edge of one sheet into the central 20 portion of the other sheet, as will be understood.

While the invention has been disclosed in the embodiment herein shown, it is understood that various changes in structure and 25 arrangement, and mechanical equivalents, are contemplated as being within the scope of the invention, now to be set forth in claims.

What we claim is:

1. A sheet interfolding machine comprising 30 a plurality of coacting drums, each drum being rotatable and having thereon pinch rolls and a pusher in alternate arrangement, one of the pinch rolls being rotatable and making a revolution to each revolution of the drum which carries it; and means for rotating the drums whereby a pusher on one drum will always coat with the pinch rolls on the other drum, these members being brought into operative relationship by rotation of the drums.

2. A sheet-interfolding machine including 35 a drum; a folding instrumentality arranged upon the drum comprising a pinch-roll having a movable pinch-bar and a pinch-roll 40 having a fixed bar thereon.

3. A sheet-interfolding machine including 45 a drum; a folding instrumentality arranged upon the drum comprising a pinch-roll having a movable pinch-bar and a pinch-roll having a fixed bar thereon; and a pusher-element disposed upon the drum.

4. A sheet-interfolding machine comprising 50 a plurality of rotatable drums; sheet-interfolding means upon each drum and comprising a pair of coacting pinch-rolls, one having a fixed and one having a movable pinch-bar thereon; a pusher instrumentality adapted to present a web of material to the bight of the pinch-rolls; and means 55 for bringing the pusher instrumentality on one drum into coactive relation with the interfolding means upon the other drum at a predetermined point in the rotation of the drums.

5. A sheet-interfolding machine comprising

60 ing a plurality of rotatable drums; sheet-interfolding means upon each drum and comprising a pair of coacting pinch-rolls, one having a fixed and one having a movable pinch-bar thereon; a pusher instrumentality adapted to present a web of material to the bight of the pinch-rolls; means for bringing the pusher instrumentality on one drum into coactive relation with the interfolding means upon the other drum at a predetermined point in the rotation of the drums; and a cutting-instrumentality associated with and operating in timed relation to the rotation of the drums.

6. A sheet-interfolding machine comprising 65 a plurality of rotatable drums; sheet-interfolding means upon each drum and comprising a pair of coacting pinch-rolls, one having a fixed and one having a movable pinch-bar thereon; a pusher instrumentality adapted to present a web of material to the bight of the pinch-rolls; means for bringing the pusher instrumentality on one drum into coactive relation with the interfolding means upon the other drum at a predetermined point in the rotation of the drums; a cutting-instrumentality associated 70 with and operating in timed relation to the rotation of the drums; and a feeding-mechanism associated with the cutting instrumentality.

7. A sheet-interfolding machine comprising 75 a plurality of rotatable drums; sheet-interfolding means upon each drum and comprising a pair of coacting pinch-rolls, one having a fixed and one having a movable pinch-bar thereon; a pusher instrumentality adapted to present a web of material to the bight of the pinch-rolls; means for bringing the pusher instrumentality on one drum into coactive relation with the interfolding means upon the other drum at a predetermined point in the rotation of the drums; and a counting-mechanism associated 80 with the drums and adapted to count the material interfolded thereby.

8. A sheet interfolding machine comprising 85 juxtaposed drums; shafts in definite predetermined relation to the drums and upon which the drums are rotatable; a pinion on each shaft; a folding instrumentality including pinch-rolls and a pusher, in alternate arrangement, disposed on each drum; pinions carried by these rolls and pushers; and means, comprising gearing, connecting the pinions and drum shafts, whereby the pusher on one drum will always be operatively presented to the bight of the pinch-rolls on a juxtaposed drum, when the drums 90 are rotated.

9. A sheet interfolding machine comprising 95 juxtaposed drums; shafts in definite predetermined relation to the drums and upon which the drums are rotatable; a pinion on each shaft; a folding instrumentality

- including pinch rolls and a pusher, in alternate arrangement, disposed on each drum; pinions carried by these rolls and pushers; means, comprising gearing, connecting the pinions and drum shafts, whereby the pusher on one drum will always be operatively presented to the bight of the pinch rolls on a juxtaposed drum, when the drums are rotated; said pinch rolls including a fixed and a movable member; and the gearing connecting the rolls and shaft being arranged always to maintain one member in a predetermined position with relation to its drum shaft, and to rotate the other member.
15. 10. A sheet-interfolding machine comprising juxtaposed drums; shafts in definite predetermined relation to the drums and upon which the drums are rotatable; a pinion on each shaft; a folding instrumentality including pinch rolls and a pusher, in alternate arrangement, disposed on each drum; pinions carried by these rolls and pushers; means, comprising gearing, connecting the pinions and drum shafts, whereby the pusher on one drum will always be operatively presented to the bight of the pinch rolls on a juxtaposed drum, when the drums are rotated; said pinch rolls including a fixed and a movable member; gearing connecting the rolls and shaft being arranged always to maintain one member in a predetermined position with relation to its drum shaft, and to rotate the other member; and gearing connecting the drum shafts, whereby the pusher on one drum will always bear a fixed relation to the drum shaft upon which it is mounted, and operatively present itself to the rolls in the other drum at a fixed point in the rotation of the drums.
40. 11. A sheet-interfolding mechanism including a drum; a shaft in fixed relation to the drum and upon which the drum is rotatable; a pinch-roll mounted upon the drum; a pinion carried by the drum-shaft; a pinion carried by the pinch-roll; and means, including gearing, for maintaining the pinch-roll in fixed position during any point in the rotation of the drum.
12. A sheet-interfolding mechanism including a drum; a shaft in fixed position with relation to the drum and upon which the drum is rotatable; a pinch-roll carried by the drum; a pinch-bar mounted on the pinch-roll; a pinion disposed upon the drum-shaft; a pinion on the pinch-roll; and means, including gearing, connecting these pinions, whereby the pinch-bar on the pinch-roll will always maintain its initial position at any point in the rotation of the drum.
65. 13. A sheet-interfolding mechanism including a drum; a plurality of coacting interfolding rolls mounted on the drum; a fixed pinch-bar carried by one roll; a movable pinch-bar carried by the other and adapted to coact with the fixed pinch-bar; a shaft in fixed relation to the drum and upon which the drum is rotatable; a pinion on each coacting interfolding roll, said latter pinions being in mesh; and means including gearing for causing rotation of one of the rolls.
14. A sheet-interfolding mechanism including a drum; a plurality of coacting interfolding rolls mounted on the drum; a fixed pinch-bar carried by one roll; a movable pinch-bar carried by the other and adapted to coact with the fixed pinch-bar; a shaft in fixed relation to the drum and upon which the drum is rotatable; a pinion on the drum-shaft; a pinion on each coacting interfolding roll, said latter pinions being in mesh; means including gearing for causing rotation of one of the rolls; and means for causing an interaction between the pinch-bars at a predetermined point in the rotation of the drum.
15. 15. A sheet-interfolding mechanism including a drum; a plurality of coacting interfolding rolls mounted on the drum; a fixed pinch-bar carried by one roll; a movable pinch-bar carried by the other and adapted to coact with the fixed pinch-bar; a shaft in fixed relation to the drum and upon which the drum is rotatable; a pinion on the drum-shaft; a pinion on each coacting interfolding roll, said latter pinions being in mesh; means including gearing for causing rotation of one of the rolls; and means, including gearing, for maintaining one of the bars in fixed position at any point in the rotation of the drum and causing the other to rotate.
16. A sheet-interfolding mechanism including a drum; a plurality of coacting interfolding rolls mounted on the drum; a fixed pinch-bar carried by one roll; a movable pinch-bar carried by the other and adapted to coact with the fixed pinch-bar; a shaft in fixed relation to the drum and upon which the drum is rotatable; a pinion on the drum-shaft; a pinion on each coacting interfolding roll, said latter pinions being in mesh; means including gearing for causing rotation of one of the rolls; and means, including gearing, for maintaining one of the bars in fixed position at any point in the rotation of the drum and causing the other to rotate and come into cooperative engagement with the other pinch-bar at a set point in the rotation of the drum.
17. A sheet-interfolding mechanism including rotatable drums; sheet folding rolls and a pusher disposed in alternate arrangement on each drum; means for effecting coaction between a pusher on one drum and sheet folding rolls on another drum at a predetermined point during the rotation of the drums; and means for maintaining the pushers in the position they occupy when

coacting with the sheet-folding rolls, unchanged by the rotation of the drums.

18. A sheet interfolding mechanism including rotatable drums; sheet folding rolls and a pusher disposed in alternate arrangement on each drum; means for effecting coaction between a pusher on one drum and sheet folding rolls on another drum at a certain point in the rotation of the drums, one of the folding rolls being rotatable and rotating at least once to each revolution of the drum which carries it; and means for maintaining a pusher in definite position with relation to the sheet folding rolls at any point in the rotation of the drums.

19. A sheet interfolding mechanism including rotatable drums; sheet folding rolls and a pusher disposed in alternate arrangement on each drum; means for effecting coaction between a pusher on one drum and sheet folding rolls on another drum at a certain point in the rotation of the drums, one of the sheet folding rolls and the pushers being always maintained in a fixed predetermined position, unchanged by the rotation of the drum; and means for cutting material from a web for presentation to the drums.

20. A sheet interfolding mechanism including rotatable drums; sheet folding rolls and a pusher disposed in alternate arrangement on each drum; means for effecting coaction between a pusher on one drum and sheet folding rolls on another drum at a certain point in the rotation of the drums, one of the sheet folding rolls and the pushers being always maintained in a fixed predetermined position, unchanged by the rotation of the drum; and means for removing the interfolded material from the drums.

21. A sheet-interfolding machine comprising a plurality of rotatable drums; sheet-interfolding rolls carried by each drum; pusher-rolls carried by each drum; pinch-bars disposed upon the interfolding-rolls; a pusher-bar on each pusher-roll; a shaft in fixed relation to each drum and upon which each drum rotates; a pinion on each shaft; a pinion on each pusher-roll; intermeshed pinions on the interfolding-rolls; and means, including gearing, for maintaining the pusher-bars on one drum in a position always to coact with interfolding-rolls on the other drum at a predetermined point in the rotation of the drums.

22. A sheet-interfolding machine comprising a plurality of rotatable drums; sheet-interfolding rolls carried by each drum; pusher-rolls carried by each drum; pinch-bars disposed upon the interfolding rolls; a pusher-bar on each pusher-roll; a shaft in fixed relation to each drum and upon which each drum rotates; a pinion on each shaft; a pinion on each pusher-roll; inter-

meshed pinions on the interfolding-rolls; means, including gearing, for maintaining the pusher-bars on one drum in a position always to coact with interfolding-rolls on the other drum at a predetermined point in the rotation of the drums; and means including gearing, for causing a rotation of one interfolding-roll with relation to the other during the rotation of the drum.

23. A sheet-interfolding machine comprising a plurality of rotatable drums; sheet-interfolding rolls carried by each drum; pusher-rolls carried by each drum; pinch-bars disposed upon the interfolding rolls; a pusher-bar on each pusher-roll; a shaft in fixed relation to each drum and upon which each drum rotates; a pinion on each shaft; a pinion on each pusher-roll; intermeshed pinions on the interfolding-rolls; means, including gearing, for maintaining the pusher-bars on one drum in a position always to coact with interfolding-rolls on the other drum at a predetermined point in the rotation of the drums; and means, including gearing, for maintaining the pinch-bar on one roll in fixed position at any point in the rotation of the drums.

24. A sheet-interfolding machine comprising a plurality of rotatable drums; sheet-interfolding rolls carried by each drum; pusher-rolls carried by each drum; pinch-bars disposed upon the interfolding-rolls; a pusher-bar on each pusher-roll; a shaft in fixed relation to each drum and upon which each drum rotates; a pinion on each shaft; a pinion on each pusher-roll; intermeshed pinions on the interfolding-rolls; means, including gearing, for maintaining the pusher-bars on one drum in a position always to coact with interfolding-rolls on the other drum at a predetermined point in the rotation of the drums; and means, including gearing, for maintaining the pinch-bar on one roll in fixed position at any point in the rotation of the drums.

25. A sheet-interfolding machine comprising a plurality of rotatable drums; sheet-interfolding rolls carried by each drum; pusher-rolls carried by each drum; pinch-bars disposed upon the interfolding-rolls; a pusher-bar on each pusher-roll; a shaft in fixed relation to each drum and upon which each drum rotates; a pinion on each shaft; a pinion on each pusher-roll; intermeshed pinions on the interfolding-rolls; means, including gearing, for maintaining the pusher-bars on one drum in a position always to coact with interfolding-rolls on the other drum at a predetermined point in the rotation of the drums; cutter-mechanism associated with the drums; counting-mechanism associated therewith also; and means

for driving all of these mechanisms in synchronism.

26. A sheet-interfolding machine including a drum; a folding instrumentality arranged thereon and comprising pinch-rolls; and a yieldably mounted pinch-bar associated with said rolls.

27. A sheet-interfolding machine comprising a plurality of rotatable drums; sheet-interfolding means upon each drum and comprising coacting pinch-rolls; a yieldably mounted pinch-bar associated with said rolls; a pusher instrumentality adapted to present a web of material to the bight of the pinch-rolls; and means for bringing the pusher instrumentality on one drum into coactive relation with the interfolding means upon the other drum at a predetermined point in the rotation of the drums.

28. A sheet-interfolding mechanism including a drum; a plurality of interfolding rolls mounted on the drum; a yieldably mounted pinch-bar associated with the rolls; a shaft in fixed relation to the drum and upon which the drum is rotatable; a pinion on the drum-shaft; a pinion on each interfolding roll, said pinions being in mesh; and means including gearing for causing rotation of one of the rolls.

29. A sheet interfolding instrumentality comprising a fixed shaft; a pinion on the shaft; a drum rotatably mounted on the shaft; a plurality of coacting interfolding rolls, arranged in pairs around the drum; gearing connecting the rolls of each pair; and a plurality of gears of equal dimensions connecting the pinion on the drum shaft with one of the gears on the rolls, there being one connecting gear for each set of rolls.

30. A sheet interfolding instrumentality comprising a fixed shaft; a pinion on the shaft; a drum rotatably mounted on the shaft; a plurality of coacting interfolding rolls, arranged in pairs around the drum; gearing connecting the rolls of each pair; a plurality of gears of equal dimensions connecting the pinion on the drum shaft with one of the gears on the rolls, there being one connecting gear for each set of rolls; a pusher disposed between each set of interfolding rolls; and a gear on each pusher, connected with one of the equal dimension gears which operate the interfolding rolls.

31. A sheet interfolding instrumentality comprising a fixed shaft; a pinion on the shaft; a drum rotatably mounted on the shaft; a plurality of coacting interfolding rolls, arranged in pairs around the drum; gearing connecting the rolls of each pair; a plurality of gears of equal dimensions connecting the pinion on the drum shaft with one of the gears on the rolls, there being one connecting gear for each set of rolls; said drum comprising end sections mounted on the shaft; mounting for the

rolls disposed on the end sections; and a cylindrical body portion connecting the end sections.

32. A sheet interfolding instrumentality comprising a fixed shaft; a pinion on the shaft; a drum rotatably mounted on the shaft; a plurality of coacting interfolding rolls, arranged in pairs around the drum; gearing connecting the rolls of each pair; a plurality of gears of equal dimensions connecting the pinion on the drum shaft with one of the gears on the rolls, there being one connecting gear for each set of rolls; said drum comprising end sections mounted on the shaft; mounting for the rolls disposed on the end sections; and a cylindrical body portion connecting the end sections; said body portion being provided with openings through which the rolls are adapted to operate.

33. A sheet interfolding machine comprising a frame; a plurality of drum-supporting shafts mounted thereon; a drum rotatably mounted on each shaft; each drum having mounted thereon, in alternate arrangement, a pair of pinch rolls and a pusher; a pinion on each drum shaft; a gear on each pusher; gearing connecting the rolls of each set of pinch rolls; and gears of equal ratio connecting the pinion on each drum shaft with one of the gears on the pinch rolls and with the pusher; a main drive from a source of power; and a driving connection between the main drive and one of the drums.

34. A sheet interfolding machine comprising a frame; a plurality of drum-supporting shafts mounted thereon; a drum rotatably mounted on each shaft; each drum having mounted thereon, in alternate arrangement, a pair of pinch rolls and a pusher; a pinion on each drum shaft; a gear on each pusher; gearing connecting the rolls of each set of pinch rolls; and gears of equal ratio connecting the pinion on each drum shaft with one of the gears on the pinch rolls and with the pusher; a main drive from a source of power; a driving connection between the main drive and one of the drums; an instrumentality including feed rolls for feeding a web of material to the drums; and a driving connection between the feed rolls and the main drive.

35. A sheet interfolding machine comprising a frame; a plurality of drum-supporting shafts mounted thereon; a drum rotatably mounted on each shaft; each drum having mounted thereon, in alternate arrangement, a pair of pinch rolls and a pusher; a pinion on each drum shaft; a gear on each pusher; gearing connecting the rolls of each set of pinch rolls; and gears of equal ratio connecting the pinion on each drum shaft with one of the gears on the pinch rolls and with the pusher; a main drive from a source of power; a driving connection between the

main drive and one of the drums; an instrumentality including feed rolls for feeding a web of material to the drums; a driving connection between the feed rolls and the main 5 drive; and a cutting instrumentality disposed between the feed rolls and drums.

36. A sheet interfolding machine comprising a frame; a plurality of drum-supporting shafts mounted thereon; a drum rotatably 10 mounted on each shaft; each drum having mounted thereon, in alternate arrangement, a pair of pinch rolls and a pusher; a pinion on each drum shaft; a gear on each pusher; gearing connecting the rolls of each set of 15 pinch rolls; and gears of equal ratio connecting the pinion on each drum shaft with one of the gears on the pinch rolls and with the pusher; a main drive from a source of power; a driving connection between the feed rolls and the main 20 drive; a cutting instrumentality disposed between the feed rolls and drums; said cutting instrumentality including a fixed cutter; rotating cutters arranged to cooperate 25 with the fixed cutter; a driving connection between the rotating cutters and the main drive; the rotating cutters being arranged to alternately coat with the fixed cutter, whereby a double web may be cut while being fed to the drums, one edge of a cut sheet being disposed between the end edges of the next succeeding sheet, and the pusher on one drum being arranged to force the 30 end edge of a cut sheet and a central portion of the next succeeding sheet into the bight of the pinch rolls on the other drum at a predetermined point in their rotation.

37. A sheet interfolding machine comprising a frame; a plurality of drum-supporting shafts mounted thereon; a drum rotatably mounted on each shaft; each drum having 35 mounted thereon, in alternate arrangement, a pair of pinch rolls and a pusher; a pinion on each drum shaft; a gear on each pusher; gearing connecting the rolls of each set of 40 pinch rolls; and gears of equal ratio connecting the pinion on each drum shaft with one of the gears on the pinch rolls and with the pusher; a main drive from a source of power; a driving connection between the main 45 drive and one of the drums; an instrumentality including feed rolls for feeding a web of material to the drums; a driving connection between the feed rolls and the main drive; a cutting instrumentality disposed between the feed rolls and drums; said 50 cutting instrumentality including a fixed cutter; rotating cutters arranged to cooperate with the fixed cutter; and a driving connection between the rotating cutters and the main drive.

38. A sheet interfolding machine comprising a frame; a plurality of drum-supporting shafts mounted thereon; a drum rotatably mounted on each shaft; each drum having 55 mounted thereon, in alternate arrangement, a pair of pinch rolls and a pusher; a pinion on each drum shaft; a gear on each pusher; gearing connecting the rolls of each set of 60 pinch rolls; and gears of equal ratio connecting the pinion on each drum shaft with one of the gears on the pinch rolls and with the pusher; a main drive from a source of power; and a driving connection between the main drive and one of the drums; said 65 pinch rolls having coacting pinching surfaces disposed thereon and arranged to be operated by the gearing to maintain one surface always in predetermined fixed position while the drum rotates around its supporting shaft.

39. A sheet interfolding machine comprising a frame; a plurality of drum-supporting shafts mounted thereon; a drum rotatably mounted on each shaft; each drum having mounted thereon, in alternate arrangement, a pair of pinch rolls and a pusher; a pinion on each drum shaft; a gear on each pusher; gearing connecting the rolls of each set of 70 pinch rolls; and gears of equal ratio connecting the pinion on each drum shaft with one of the gears on the pinch rolls and with the pusher; a main drive from a source of power; a driving connection between the main drive and one of the drums; an instrumentality including feed rolls for feeding a web of material to the drums; a driving connection between the feed rolls and the main 75 drive; a cutting instrumentality disposed between the feed rolls and drums; said cutting instrumentality including a fixed cutter; rotating cutters arranged to cooperate 80 with the fixed cutter; a driving connection between the rotating cutters and the main drive; the rotating cutters being arranged to alternately coat with the fixed cutter, whereby a double web may be cut while being fed to the drums, one edge of a cut sheet being disposed between the end edges of the next succeeding sheet, and the pusher on one drum being arranged to force the end edge of a cut sheet and a central portion of the next succeeding sheet into the bight of the pinch rolls on the other drum at a predetermined point in their rotation.

40. A sheet interfolding machine comprising a frame; a plurality of drum-supporting shafts mounted thereon; a drum rotatably mounted on each shaft; each drum having mounted thereon, in alternate arrangement, a pair of pinch rolls and a pusher; a pinion on each drum shaft; a gear on each pusher; gearing connecting the rolls of each set of 90 pinch rolls; and gears of equal ratio connecting the pinion on each drum shaft with one of the gears on the pinch rolls and with the pusher; a main drive from a source of power; and a driving connection between the main drive and one of the drums; said 95 pinch rolls having coacting pinching surfaces disposed thereon and arranged to be operated by the gearing to maintain one surface always in predetermined fixed position while the drum rotates around its supporting shaft.

41. A sheet interfolding machine comprising a frame; a plurality of drum-supporting shafts mounted thereon; a drum rotatably mounted on each shaft; each drum having mounted thereon, in alternate arrangement, a pair of pinch rolls and a pusher; a pinion on each drum shaft; a gear on each pusher; gearing connecting the rolls of each set of 100 pinch rolls; and gears of equal ratio connecting the pinion on each drum shaft with one of the gears on the pinch rolls and with the pusher; a main drive from a source of power; and a driving connection between the main drive and one of the drums; said 105 pinch rolls having coacting pinching surfaces disposed thereon and arranged to be operated by the gearing to maintain one surface always in predetermined fixed position while the drum rotates around its supporting shaft.

42. A sheet interfolding machine comprising a frame; a plurality of drum-supporting shafts mounted thereon; a drum rotatably mounted on each shaft; each drum having mounted thereon, in alternate arrangement, a pair of pinch rolls and a pusher; a pinion on each drum shaft; a gear on each pusher; gearing connecting the rolls of each set of 110 pinch rolls; and gears of equal ratio connecting the pinion on each drum shaft with one of the gears on the pinch rolls and with the pusher; a main drive from a source of power; and a driving connection between the main drive and one of the drums; said 115 pinch rolls having coacting pinching surfaces disposed thereon and arranged to be operated by the gearing to maintain one surface always in predetermined fixed position while the drum rotates around its supporting shaft.

43. A sheet interfolding machine comprising a frame; a plurality of drum-supporting shafts mounted thereon; a drum rotatably mounted on each shaft; each drum having mounted thereon, in alternate arrangement, a pair of pinch rolls and a pusher; a pinion on each drum shaft; a gear on each pusher; gearing connecting the rolls of each set of 120 pinch rolls; and gears of equal ratio connecting the pinion on each drum shaft with one of the gears on the pinch rolls and with the pusher; a main drive from a source of power; and a driving connection between the main drive and one of the drums; said 125 pinch rolls having coacting pinching surfaces disposed thereon and arranged to be operated by the gearing to maintain one 130 surface always in predetermined fixed position while the drum rotates around its supporting shaft.

surface always in predetermined fixed position while the drum rotates around its supporting shaft, the other pinching surface being arranged to rotate with relation to the fixed surface and coact with the fixed surface at a predetermined point during the rotation of the drums.

41. A sheet interfolding machine comprising a frame; a plurality of drum-supporting shafts mounted thereon; a drum rotatably mounted on each shaft; each drum having mounted thereon, in alternate arrangement, a pair of pinch rolls and a pusher; a pinion on each drum shaft; a gear on each pusher; gearing connecting the rolls of each set of pinch rolls; and gears of equal ratio connecting the pinion on each drum shaft with one of the gears on the pinch rolls and with the pusher; a main drive from a source of power; and a driving connection between the main drive and one of the drums; an instrumentality including feed rolls for feeding a web of material to the drums; a driving connection between the feed rolls and the main drive; a cutting instrumentality disposed between the feed rolls and drums; said cutting instrumentality including a fixed cutter; rotating cutters arranged to cooperate with the fixed cutter; a driving connection between the rotating cutters and the main drive; the rotating cutters being arranged to alternately coact with the fixed cutter, whereby a double web may be cut while being fed to the drums, one edge of a cut sheet being disposed between the end edges of the next succeeding sheet, and the pusher on one drum being arranged to force the end edge of a cut sheet and a central portion of the next succeeding sheet into the bight of the pinch rolls on the other drum at a predetermined point in their rotation; and means for removing the interfolded sheets from the drums; said means including a guideway; a conveyor operatively associated therewith, and means for driving the conveyor.

42. A sheet interfolding machine comprising a frame; a plurality of drum-supporting shafts mounted thereon; a drum rotatably mounted on each shaft; each drum having mounted thereon, in alternate arrangement, a pair of pinch rolls and a pusher; a pinion on each drum shaft; a gear on each pusher; gearing connecting the rolls of each set of pinch rolls; and gears of equal ratio connecting the pinion on each drum shaft with one of the gears on the pinch rolls and with the pusher; a main drive from a source of power; and a driving connection between the main drive and one of the drums; said pinch rolls having coacting pinching surfaces disposed thereon and arranged to be operated by the gearing to maintain one surface always in predetermined fixed position while the drum rotates around its supporting shaft, the other pinching surface being arranged to rotate with relation to the fixed surface and coact with the fixed surface at a predetermined point during the rotation of the drums; said pinching surfaces being arranged to separate at a point approximately sixty degrees beyond their point of contact to release material acted upon.

43. A sheet interfolding machine comprising a frame; a plurality of drum-supporting shafts mounted thereon; a drum

rotatably mounted on each shaft; each drum having mounted thereon, in alternate arrangement, a pair of pinch rolls and a pusher; a pinion on each drum shaft; a gear on each pusher; gearing connecting the rolls of each set of pinch rolls; and gears of equal ratio connecting the pinion on each drum shaft with one of the gears on the pinch rolls and with the pusher; a main drive from a source of power; a driving connection between the main drive and one of the drums; an instrumentality including feed rolls for feeding a web of material to the drums; a driving connection between the feed rolls and the main drive; a cutting instrumentality disposed between the feed rolls and drums; said cutting instrumentality including a fixed cutter; rotating cutters arranged to cooperate with the fixed cutter; a driving connection between the rotating cutters and the main drive; the rotating cutters being arranged to alternately coact with the fixed cutter, whereby a double web may be cut while being fed to the drums, one edge of a cut sheet being disposed between the end edges of the next succeeding sheet, and the pusher on one drum being arranged to force the end edge of a cut sheet and a central portion of the next succeeding sheet into the bight of the pinch rolls on the other drum at a predetermined point in their rotation; and means for removing the interfolded sheets from the drums; said means including a guideway; a conveyor operatively associated therewith, and means for driving the conveyor.

44. A sheet interfolding machine comprising a frame; a plurality of drum-supporting shafts mounted thereon; a drum rotatably mounted on each shaft; each drum having mounted thereon, in alternate arrangement, a pair of pinch rolls and a pusher; a pinion on each drum shaft; a gear on each pusher; gearing connecting the rolls of each set of pinch rolls; and gears of equal ratio connecting the pinion on each drum shaft with one of the gears on the pinch rolls and with the pusher; a main drive from a source of power; a driving connection between the main drive and one of the drums; and a driving connection between the drums whereby they are driven in synchronism.

45. A sheet interfolding mechanism including rotatable drums; sheet folding rolls and a pusher disposed in alternate arrangement on each drum; means for effecting coaction between a pusher on one drum and the folding rolls on another drum at a predetermined point during the rotation of the drums; means for maintaining the pushers in their coacting position, unchanged during rotation of the drums; and means for effecting a rotation of one folding roll with relation to the other of the pair while

- maintaining the other roll in the position it occupies at coaction with the pusher, unchanged during rotation of the drum.
46. In an interfolding machine, a plurality of roll-carrying drums, clamping rollers on each of the drums and bodily movable thereon in a direction having a lateral component, a plurality of tucker devices on each drum and longitudinally arranged thereon with respect to each pair of rollers thereon, and means common to the rollers and tucker devices on each drum for simultaneously rotating said rollers continuously in a direction adapted to draw material therebetween and to maintain the tucker devices in a predetermined relation thereto.
47. In an interfolding machine, a plurality of roll-carrying drums, clamping rollers on each of the drums and bodily movable thereon in a direction having a lateral component, a plurality of tucker devices on each drum and longitudinally arranged thereon with respect to each pair of rollers thereon, means common to the rollers and tucker devices on each drum for simultaneously rotating said rollers continuously in a direction adapted to draw material therebetween and to maintain the tucker devices in a predetermined relation thereto, and means associated with the rollers for releasing such material from between the same at a predetermined point in the bodily movement thereof.
48. In an interfolding machine, a plurality of roll-carrying drums, a plurality of pairs of clamping rollers on each of the drums and bodily movable thereon in a direction having a lateral component, a plurality of tucker devices on each drum and longitudinally arranged thereon with respect to each pair of rollers thereon, each tucker device on each drum having rotation therein, and means common to the rollers and tucker devices on each drum for simultaneously rotating the rollers continuously in a direction adapted to draw material therebetween and to maintain the tucker devices in a predetermined relation thereto.
49. In an interfolding machine, a plurality of roll-carrying drums, a plurality of pairs of clamping rollers on each of the drums and bodily movable thereon in a direction having a lateral component, a plurality of tucker devices on each drum and longitudinally arranged thereon with respect to each pair of rollers thereon, each tucker device on each drum having rotation therein, means common to the rollers and
- tucker devices on each drum for simultaneously rotating the rollers continuously in a direction adapted to draw material therebetween and to maintain the tucker devices in a predetermined relation thereto, and means associated with the rollers for releasing such material from between the same at a predetermined point in the bodily movement thereof.
50. A sheet interfolding machine including a drum; a folding instrumentality arranged upon the drum comprising a pair of pinch-rolls and yieldingly cooperating pinch-bars on the respective pinch-rolls.
51. A sheet interfolding machine including a drum; a folding instrumentality arranged upon the drum comprising a pair of pinch-rolls and yieldingly cooperating pinch-bars on the respective pinch-rolls; and a pusher-element disposed upon the drum.
52. A sheet interfolding machine comprising a plurality of coacting carriers, each carrier being rotatable and having thereon a plurality of sets of folding devices, each set comprising movable sheet-engaging-elements, and pushers in alternate arrangement therewith; one of the folding-elements being movable in timed relation to the other element and to a coacting pusher during each revolution of the carrier which carries it, and means for rotating the carriers whereby one of the pushers on one of the carriers will coact with one of the sets of folding elements on the other carrier, these members being brought into operative relationship by rotation of the carriers.
53. A sheet interfolding machine comprising a plurality of coacting carriers, each carrier being rotatable and having thereon a plurality of sets of folding devices, each set comprising sheet-engaging-elements, and pushers in alternate arrangement therewith; one of the folding elements having rotative movement in respect to the other element to effect a pinching action thereon during each revolution of the carrier which carries it; and means for rotating the carriers whereby one of the pushers on one of the carriers will coact with one of the sets of folding elements on the other carrier, these members being brought into operative relationship by rotation of the carriers.

In testimony whereof we affix our signatures.

WILLIAM H. CANNARD.
GLENN A. SHAFFER.
